COSMETIC CONTAINER

Arthur R. Botham, New York, N. Y., assignor to
 Coty, Inc., Wilmington, Del., a corporation of
 Delaware

Application November 18, 1938, Serial No. 241,099

4 Claims. (Cl. 132—79)

My invention relates to cosmetic containers and more particularly to a device whereby a plurality of cosmetics are maintained in assembled relation.

5 Lip rouge and face powder are the most widely and frequently used cosmetics and the present invention is particularly concerned therewith.

One of the objects of my invention is to provide a lip rouge-face powder combination assembly wherein said elements are disposed in their respective containers each container operating as a handle for the device while the other container is in use.

Another object of my invention is to provide 15 such a combination wherein each cosmetic and its container shall be maintained distinct from any other cosmetic and container, the connection operating merely to maintain the several containers in permanent juxtaposition.

20 Another object of my invention is to produce such an assembly which shall possess a degree of flexibility necessary to permit the device to accommodate itself to its environment, usually the irregular confines of a lady's handbag.

25 Another and very important object of my invention is to produce an inseparable cosmetic combination whose assembly shall be most easily and economically effected and shall also effect great savings in the manufacture of these devices.

30 Other objects of my invention will be apparent from the following description it being understood that the above general statements of the objects of my invention are intended to explain and not to limit it in any manner.

35 Fig. 1 is a front view of the combination partly broken away, the lip rouge casing being shown in section.

Fig. 2 is a side view of the device illustrating the action of the lip rouge casing.

40 Fig. 3 is a section on the line 3—3 of Fig. 1.

Fig. 4 is a front view of a modification, partly in section.

In the drawing 10 represents a base, bearing integral therewith the body member 11, which 45 together with the cover member 12 constitute the face powder container. Said face powder is designated as 13 and a powder puff as 14.

The body 10 is formed with two oppositely disposed lugs or trunnions 15 which furnish an 50 axis on which the lip rouge body member 16 may turn. A cover member 17 may be secured frictionally to the body member 16 and the lip stick 18 is retained in said body member.

Fig. 4 shows another embodiment wherein the 55 cover member 17a is likewise pivotally or swing-

ably secured to the base 10a and the lip rouge body member 16a is removable from the assembly.

However, in either embodiment, it is obvious that an intimate assembly between these related products has been secured while maintaining them separately usable and providing a flexibility which enables the device to be disposed in small and irregular confines. While the use of a flexible string or chain may have been 10 suggested to effect the above results, such an expedient has proven undesirable since the chain causes entanglement with other objects and is difficult of assembly, unduly increasing the cost of manufacture. It is also apparent that the 15 disposition of the containers enables either one of them to be used as a handle for the device when the other container is in use.

The device is preferably but not necessarily 20 made of a plastic material which possesses a resilience effective to permit the trunnions 15 to be separated and then permitted to spring into recesses formed in the lip rouge casing. Thus it is obvious that the labor of assembly 25 is reduced to a minimum. A resilient metal is also usable.

I have shown preferred embodiments of my 30 invention but it is obvious that numerous changes and omissions may be made without departing from its spirit. For example, the pivotal action of the lip rouge casing may be accomplished by providing lugs thereon which may be accommodated in recesses formed in the base 10 instead of the trunnions 15 and it is understood 35 that my invention covers this variation.

I claim:

1. A cosmetic assembly comprising a base for supporting a compact thereon and arms formed integral with said base at one end thereof and 40 extending longitudinally in the same plane as said base, said arms being adapted to swingably connect a cosmetic stick to said base.

2. A toilet device comprising in combination a base, a cosmetic carrier mounted on the periphery of said base, and arms formed integral with said base and extending longitudinally in the same plane so as to constitute a pair of trunnions adapted to swingably support a cosmetic stick. 45

3. A toilet device comprising a flat base having an end portion thereof and an adjacent section of the perimeter cut away to form a C-shaped opening, the legs of said C-shaped open- 50 55

ing being adapted to serve as an axis for swingably supporting a cosmetic stick.

4. A toilet device comprising a flat base formed of resilient material, a cosmetic carrier mounted on the periphery of said base, said base having an end portion and an adjacent section of the

perimeter cut away to form a C-shaped opening, the legs of said C-shaped opening being adapted to serve as trunnions for swingably supporting a cosmetic stick by frictional engagement.

ARTHUR R. BOTHAM.
